UNITED STATES PATENT OFFICE.

WILLIAM S. HAMM, OF NEWTON, MASSACHUSETTS, ASSIGNOR TO AUGUSTUS SEAVER, OF BOSTON, MASSACHUSETTS.

MACHINE FOR STRETCHING UPPERS.

SPECIFICATION forming part of Letters Patent No. 596,325, dated December 28, 1897.

Application filed January 22, 1897. Serial No. 620,208. (No model.)

To all whom it may concern:

Be it known that I, WILLIAM S. HAMM, of Newton, in the county of Middlesex and State of Massachusetts, have invented certain new and useful Improvements in Machines for Stretching Uppers, of which the following is a specification.

This invention relates to machines for stretching uppers over their lasts prior to their being secured to the insoles; and it has for its object to provide a machine which may be operated to secure the drawing of the uppers over the lasts efficaciously and with the least expenditure of power and which will be so constructed that after an upper has been drawn taut the last may be reversed and the upper secured to the insole without removing them from the machine.

To these ends the invention consists of a machine embodying those features of construction and arrangement which are illustrated in the drawings and which are now to be described in detail, and then pointed out in the claims hereto annexed.

Reference is to be had to the accompanying drawings, forming a part of this specification, in which like letters of reference indicate the same parts or features wherever they occur.

Of the drawings, Figure 1 is a side elevation of one form of machine embodying my improvements. Fig. 2 is a front end elevation of the same. Fig. 3 is a plan view of the same. Fig. 4 is a front end elevation of the machine with the base of the standard broken away and the head of the machine reversed or swung upon its axis, so as to bring the sole uppermost for the purpose of securing the upper thereto. Figs. 5, 6, and 7 are cross-sections showing the action of the grippers in grasping the edges of the upper and drawing it taut on the last. Fig. 8 is a section on the line 8 8 of Fig. 1. Fig. 9 is a section on the line 9 9 of Fig. 1. Fig. 10 is an enlarged section on the line 10 10 of Fig. 2. Fig. 11 is an enlarged section on the line 11 11 of Fig. 3. Fig. 12 is an enlarged section on the line 12 12 of Fig. 3.

In carrying out my invention, which it will be understood is not limited to those details of construction which I have elected to illustrate in the drawings and which I shall now

proceed to describe, I employ a standard *a*, having a suitable flattened base *a'* and a laterally-projecting bracket *a''*, in which are supported some of the operative parts of the machine. Upon the upper end of the standard *a* is secured a bearing-bracket *a''*, having a suitable sleeve-like bearing *a''*. The casting or head *b*, upon which are mounted the grippers for drawing the upper taut over the last, is provided with a tubular trunnion *b'*, projecting through the bearing *a''* and equipped on its other end with a notched collar *b''* and with an arm *b''*, clamped thereto, and provided with a counterbalancing-weight *b''*. The head or bracket *b* (shown in Figs. 1 and 12) is curved downwardly and forwardly and is formed with two steps or abutments *c c'*, having upwardly-projecting points *c'* to receive the last, there being a recess or cut-away portion between the steps, as more clearly shown in Fig. 12. The head is provided with an upwardly-projecting bracket *d*, in which is rotatably clamped by a cap *d'* a stud *d''*, which is formed at its forwardly-projecting end into a bearing *d''* to receive a vertically-movable bar *d''*, having a point *d''* to enter a recess in the last, as shown in Fig. 1, and to clamp it against the steps on the head or bracket *b*.

It will be seen that the bar *d''* is arranged in advance of the rear step *c*, so as to cause the last to be clamped firmly against both sets of projections *c c'*. The bar is formed for a portion of its length with rack-teeth, with which a pinion *d''* on a shaft *d''*, equipped with a hand-wheel *d''*, engages and by means of which the bar may be raised or lowered. Its upper reduced and threaded end *d''* is provided with two locking-nuts *d''*, between which and the upper end of the bearing *d''* is placed a strong helical spring *d''* of sufficient strength to raise the bar *d''* to its uppermost position. For the purpose of locking the bar at any desired position I provide a spring-held cam *d''*, secured to a stud-shaft mounted in the bearing *d''* and adapted to be held by its spring *d''* against the bar, as shown in Fig. 10. When the hand-wheel *d''* has been rotated, so as to force the bar *d''* downward, the cam *d''* bears against the said bar and locks it against upward movement. The

shaft of the cam is provided with a handle d^{14} , whereby when the cam is rocked against the stress of the spring and out of engagement with the bar the spring d^{11} will force the bar upward to its normal elevated position.

The machine is so constructed that after the last is clamped upon the steps by the bar or clamping devices just described the whole head may be rotated, so as to reverse the last and bring its sole uppermost. In order to lock the head at any desired position, the notched collar b^2 is provided, as hereinbefore stated, there being a latch e pivoted in ears e' and which is adapted to enter any one of the notches in the collar. The latch is normally held in engagement with the walls of the notches by a spring e^2 , but it is adapted to be drawn out from engagement therewith by a foot-lever e^3 , passing through the stand ard and pivoted on the base a' and having its rear end connected with the end of the latch by an adjustable link e^4 , as shown in Fig. 1. By depressing the end of the foot-lever e^3 the latch is disengaged from the collar, and the operator may then freely swing the head around in any desired position.

For the purpose of stretching the upper over the last I employ two sets of grippers on each side of the last which are arranged to draw the edges of the upper down and then under the last to entirely remove all the wrinkles and creases and fit the upper perfectly upon the last; and in addition thereto the grippers which stretch the toe portion of the upper are arranged to slide forward, so as to stretch the upper not only transversely of the last, but longitudinally thereof also.

I do not provide a gripper for the extreme toe end of the upper, as the stretching of the upper in the central longitudinal line of the last is accomplished by manually-operated pincers, which are adapted to be rested or ful-crumed in notches c^2 c^2 in the forward end of the head or bracket. Preferably the grippers on each side of the last are arranged to grasp the upper at a point between the heel and the ball or at the shank and at a point in front of the ball; and hence the first-mentioned grippers are arranged to move only downward and transversely of the last, while the latter are arranged to be moved downwardly and inward and forward by means of devices to be described.

I shall first describe the grippers which are arranged beneath the shank of the last.

Referring more particularly to Figs. 5, 6, 7, and 8, it will be seen that the head or bracket b is provided with two laterally-projecting lugs f , with grooves or depressions, in which are clamped by caps f' two bars f^2 f^2 , the ends of which are secured in brackets f^3 f^3 , which project upwardly and outwardly. The bars f^2 are preferably formed with enlarged heads f^4 , having ears or lugs f^5 , and the brackets f^3 are each formed with an inwardly-projecting lug f^6 to receive the lower end of the bar, being secured to the head f^4

by screws f^7 . (Shown in dotted lines in Fig. 8.) In the lugs f^5 of the bars f^2 are pivoted arms g g , each of which is provided at its upper end with a jaw g' , adapted to coöperate with a jaw g^3 , mounted on another arm g^2 , which is movable in parallelism to the arm g . The arms g and g^2 are connected by cross-links g^4 g^5 , which are pivoted together at their intersection and are pivoted at their upper ends to the said arms. They are each provided with a pin projecting into slots in the said arms, and the links g^5 are each provided with an extension g^6 , so that by raising or lowering the latter the jaws g' and g^3 may be caused to approach or recede from each other. For operating the two sets of grippers in unison I provide the following devices: h h' are toggle-levers pivoted together and respectively pivoted to the ends of the extensions g^6 of the links g^5 and to the upper ends of the brackets f^3 . Springs h^2 hold the jaws g' g^3 normally open and the arms g outward, the latter being provided with fingers g^7 with adjustable screws g^8 , abutting against stops g^9 on the brackets, which limit their outward movement. The springs h^2 are assisted in maintaining the arms g in their outward positions by additional springs h^3 , each of which has one end attached to a finger g^7 and the other end attached to a pin on the bracket f^3 . The head or main bracket b is provided with a socket b^{10} to receive a vertically-movable pin i , which projects thereinto and which is formed on the end of a bar i' , projecting below the head. The bar i' is provided with a cross-bar i^2 , the outer ends of which are connected by chains i^3 with the pivots h^4 of the toggle-levers h h' , so that by drawing downward on the bar i' the toggle-levers are straightened out, with the result that the edges of the upper are clamped between the jaws g' g^3 and are drawn downward and under the last, as pictured in Figs. 5, 6, and 7, which show the various positions of the parts as this is being accomplished. In order to lock the jaws in their operative locking positions, a cam i^5 is secured to a shaft i^6 , mounted in the head b and provided with a handle i^7 , as shown in Fig. 1. The spring i^8 holds the cam against the pin i , so that when the bar i' is drawn downward the cam i^5 engages it and prevents any backward movement until it is moved out of engagement therewith by the handle i^7 .

The grippers for the edges of the upper near the toe end of the last are shown in Figs. 9, 11, and 12, to which reference is to be had.

The bracket b is provided at its forward end with a slideway j to receive a carriage k , having tongues k' sliding in said slideway and held therein by strips k^2 . The carriage is adapted to be reciprocated or adjusted by a screw l , having its end threaded into a nut l' , formed in the under side of the head and having on its outer end a sleeve l^2 , formed with a hand-wheel l^3 . The screw l is formed with a flange l^4 abutting against the carriage, so that by turning the hand-wheel in one di-

rection the carriage will be forced backward or toward the standard, and by turning the hand-wheel in the other direction it will be drawn forward, as will be readily seen. The carriage is formed with two outwardly-projecting wings or plates k^{12} , suitably braced by webs k^3 and formed at their outer ends with split bearings k^4 , in which are mounted or journaled posts m . The latter may be 5 locked in position by bolts k^5 , which act to clamp the bearings k^4 firmly therearound. Projecting outward from each post is an arm m' , formed therewith and on the end of which a collar m^2 is clamped, as shown in Fig. 9. 10 Keyed to each arm m' , so as to be prevented from rotating, while free to slide longitudinally therein, is a sleeve m^3 , formed with an ear or lug m^4 , into which the screw m^5 is threaded. Each screw m^5 , which is provided 15 with a hand-wheel m^6 , passes loosely through a lug m^7 on the collar m^2 and, as just stated, is threaded into the lug m^4 on the sleeve m^3 , so that when the hand-wheel m^6 is turned in one direction or the other the sleeve m^3 is 20 forced forward or back along the arm m' . The sleeve m^3 is likewise provided with two upwardly-projecting ears m^8 , between which and in which is pivoted a lever n , which passes through an aperture m^9 in the post m . 25 and is provided on its end with a gripping-arm n' , having a jaw n^2 . The lever n rests upon a pin m^{10} , inserted in a socket in the post m and resting against a spring m^{11} , which latter rests upon a disk m^{12} , which may be 30 adjusted by a screw m^{13} to regulate the tension of the spring. The spring m^{11} is of sufficient strength to cause the pin m^{10} to hold the lever n in its uppermost position, there being an adjustable screw m^{14} , which acts as 35 a stop to limit the upward movement of said lever.

Connected to the arm n' by cross-links $o o'$, similar to those described at g^4 and g^5 , is another gripping-arm n^3 , likewise equipped with 40 a jaw n^4 to coöperate with the jaw n^2 , above referred to. The gripping-arm n^3 may be moved toward and from the gripping-arm n' and in parallelism therewith by means of chains $p p$, connected to a cross-bar q and to 45 extensions o^2 of the links o . The cross-bar q is mounted upon a stud q^3 , projecting rearward from a hanger q^4 , having a downwardly and rearwardly projecting finger q^5 for a purpose to be described, which hanger is secured 50 upon the lower end of a bar q^6 , sliding in a socket k^{14} in the carriage k . A locking-cam r on a shaft r' , mounted in the carriage k and provided with a handle r^2 , is held in engagement with the pin q^6 by a spring r^3 , so 55 that after the hanger q^4 has been depressed to cause the jaws $n^2 n^4$ to engage the edges of the upper and draw the latter downward the cam r engages the pin q^6 and holds the grippers in their operative position.

60 In drawing upon the chains $p p$ to cause the gripping of the edges of the uppers the levers

are swung downward and the upper is drawn taut by them over the last.

By mounting the grippers on the post m it is permitted to adjust the grippers so that 70 their gripping-jaws will lie parallel to the sole of the last irrespective of the particular shape of the latter—that is to say, if the toe of the last is pointed the two sets of jaws can be adjusted so that each set will be parallel to 75 the edge of the sole adjacent to it.

The rear gripping-jaws may remain parallel and do not need to be adjusted, while in order that the machine may be used for all sizes and styles of shoes it is essential that the 80 forward grippers may be adjusted to lie at any angle to each other, and hence this is one of the important features of my invention.

To assist the clamps in holding the posts against rotation when there is a lateral strain 85 on the ends of the lever $n n$, caused by the carriage being drawn forward, I provide each post m with an extension m^{15} , formed into a segmental ratchet, with the teeth of which a dog m^{16} , pivoted on the plate k^{12} , is caused to 90 engage by a spring m^{17} .

When the levers are adjusted with the posts m , the dogs m^{16} engage the teeth of the segmental ratchets and lock the posts against 95 backward rotation.

For the purpose of drawing downward upon the bar i' and the hanger q^4 to operate the grippers I provide foot-levers s and t , respectively, fulcrumed on the base a' .

In the bracket a^2 , before mentioned, I mount 100 two sliding bars s' and t' , which are connected to the foot-levers by adjustable pivoted links s^2 and t^2 and which are normally held in their raised positions by springs s^3 t^3 .

The bar s' is equipped at its upper end with 105 a yoke s^4 , with inwardly-projecting fingers s^5 , between which the bar i' may freely pass, but which will, when said bar is between them and the rod or bar s' is depressed, engage an enlargement or head t^{12} on the bar i' and draw 110 it downward. The upper end of the bar t' is provided with a head t^4 , which projects forward, so as to lie above the finger q^5 of the hanger q^4 when the head, with the grippers, is in the position shown in Fig. 1, so that when 115 the lever t is depressed the hanger q^4 is drawn downward and the grippers connected therewith consequently operated.

Upon depressing either of the foot-levers s or t the cross-bar i^2 or the cross-bar q and their 120 corresponding grippers are actuated, and upon removing the foot from said levers they are elevated by the springs s^3 or t^3 , while the grippers remain locked by the hereinbefore-described devices.

125 The operation of the machine is as follows: The insole is secured on the last by several tacks, and after the upper is drawn over the last the latter is placed on the abutments on the head, after which it is rigidly locked thereon by turning the hand-wheel d^3 until the point d^5 enters the recess in the last and forces

the latter against the points $c' c'$. Then the levers $n n$ are adjusted about their pivots until the jaws of the forward grippers are parallel to the edges of the sole of the last, and 5 the carriage is also adjusted to carry the said grippers in position to grasp the edges of the upper in front of the ball. Then the foot-lever t is depressed, which at one action causes the front gripper to tightly grip the edges of 10 the upper and draw them downward, and as the grippers begin their drawing action after having grasped the upper the hand-wheel l^3 is turned so as to feed the carriage k forward. Thus the upper is drawn taut over the last 15 downward and forward toward the toe with an even pressure on both sides of the last. After this has been accomplished the hand-wheels m^6 are rotated to force the levers m and their grippers inward under the last far 20 enough to allow of tacks being driven through the edges of the upper into the insole. Then the lever s is depressed and the grippers at the shank grasp the edges of the upper and draw the said upper taut downward and in 25 ward under the shank of the last. The extreme toe portion of the upper is lasted over by means of manually-operated pincers, which may be fulcrumed in the notches c^2 , as hereinbefore explained. The upper is now ready 30 to be tacked to the insole, so that after depressing the lever e^3 to disengage the latch e from the notched collar b^2 the operator partially revolves the whole head and brings the sole uppermost, as shown in Fig. 4, where he 35 can easily drive the tacks through the edges of the upper into the insole.

It will be observed that by constructing a machine in accordance with the foregoing I provide a revoluble abutment, which operates 40 to resist the thrust of the grippers and against which the latter exert their force in drawing an upper taut over a last, and that after the upper has been suitably stretched over the last the grippers may be disengaged 45 from the foot-levers or power devices and the whole head or abutment partially rotated, the grippers remaining locked during this operation. This is of importance in my invention, since the last being arranged sole down- 50 ward the operator may watch the upper during the stretching process to prevent it from being drawn out of shape or stretched too far on one side or the other, and if by chance the upper has been stretched too far on one 55 side by one of the front grippers he may easily adjust the grippers by means of the hand-wheels m^6 to lay it properly over the last.

The grippers are automatically locked in 60 position to maintain the upper in its stretched condition and remain so when the head is revolved; nor does the adjustment of the front grippers change their relationship to the lever t , for it will be observed that the hanger has a long finger q^5 , which extends under the 65 projecting portion of the head and slides thereunder when the carriage is adjusted. Again, by constructing the grippers as here-

inbefore described their jaws are automatically clamped together on the upper and then they are moved bodily by a single movement of the foot-lever, so that two distinct operations with two separate mechanisms for clamping the jaws together and operating the grippers are not necessary.

It will be understood that the invention is 75 not limited to the details of construction which are shown and described, since it may be embodied in machines of other forms and provided with mechanism other than that 80 illustrated in the drawings.

Having thus explained the nature of the invention and described a way of constructing and using the same, although without attempting to set forth all of the forms in 85 which it may be made or all of the modes of its use, I declare that what I claim is—

1. In a machine for stretching uppers, the combination of a reversible support affording an abutment for a last; upper grasping and stretching means carried by said support; a 90 lock to hold said means in grasping and stretching condition; and an operating member on a fixed support, the said upper grasping and stretching means and the said operating member having disconnected parts in 95 interlocking only for combined movement relative to the reversible support.

2. In a machine for stretching uppers, the combination of a support rotatively mounted for reversibility and affording an abutment 100 for a last; upper grasping and stretching means carried by said support; a lock to hold said means in grasping and stretching condition; and an operating member on a fixed support, said means and the operating member 105 having disconnected parts interlocking for combined movement relative to the reversible support, without obstructing rotary movement of the latter.

3. In a machine for stretching uppers, the 110 combination of a reversible support affording an abutment for a last; a carriage longitudinally movable on said support; upper grasping and stretching means on said carriage; a lock to hold said means in grasping and 115 stretching condition; and an operating member on a fixed support, said operating member and the grasping and stretching means having disconnected parts interlocking for combined movement relative to the reversible support, with provision for adjustment of 120 the carriage longitudinally of said support.

4. In a machine for stretching uppers, the combination of a support affording an abutment for a last; grippers movably mounted 125 on said support so as to move transversely of and toward and away from the last thereon; and a toggle between the grippers and the support and operating both to close the grippers and to move the same relatively to the 130 support.

5. In a machine for stretching uppers, the combination of a support affording an abutment for a last, an arm pivoted to the said

support and having a jaw to engage one side of an upper on such last, a complementary jaw to engage the opposite side of the upper, a lever pivotally connected with the arm and 5 with the complementary jaw, and a toggle one member of which is connected with the said lever and the other with the support.

6. A machine for stretching uppers, comprising a last, an abutment therefor, two pairs 10 of oppositely - arranged grippers, and means for causing one pair of grippers to be moved inwardly under the last, and additional means for causing the other pair of grippers to be moved longitudinally of the last.

15 7. In a machine for stretching uppers, the combination of a reversible support affording an abutment for a last; grippers on said support and arranged to act upon an upper on such last; means carried by the support for 20 closing the grippers on the upper and for moving them to stretch the same, said means including a reciprocating bar having a head or lateral projection; an automatic lock associated with said bar; and an operating member 25 on a fixed support and having a part co-acting with the projection or head on said bar to secure combined movement of the latter and the operating member relative to the reversible support.

30 8. A machine for stretching uppers, comprising a reversible abutment to receive a last, two pivoted gripping-arms pivoted to the abutment and each having a coacting gripping-arm connected thereto, a stationary 35 standard, an operating-lever mounted on said standard, and suitable connections between said lever and the gripping devices.

9. A machine for stretching uppers, comprising an abutment, gripping-jaws arranged 40 adjacent the abutment, means for closing the jaws and moving them transversely of the last, and additional means for moving said jaws longitudinally of the last.

10. A machine for stretching uppers, comprising an abutment, gripping-jaws arranged 45 adjacent the abutment, a pivoted lever for the jaws, means for closing the jaws and swinging the lever transversely of the last, and means for adjusting said lever longitudinally toward and from said last.

50 11. A machine for stretching uppers, comprising an abutment, gripping-jaws arranged adjacent the abutment, a pivoted lever for

the jaws bodily movable in the direction of its length, means for closing the jaws and 55 swinging the lever transversely of the last, means for adjusting said lever longitudinally toward and from the last, and means for adjusting said lever bodily longitudinally of the last.

60 12. A machine for stretching uppers, comprising an abutment, gripping-jaws arranged adjacent the abutment, a pivoted lever for the jaws, means for closing the jaws and swinging the lever transversely of the last, 65 and means for adjusting said lever to present the jaws with their edges parallel to the edge of the sole of the last.

13. A machine for stretching uppers, comprising an abutment, gripping-jaws arranged 70 adjacent the abutment, means for causing the jaws to stretch the upper, a pivotal support for said jaws adjustable to present their edges parallel to the edge of the sole of the last, and means for locking said support against backward movement on its pivot, substantially as described.

14. A machine for stretching uppers comprising an abutment adapted to receive a last, gripping-jaws mounted upon the said abutment, a carriage movable relatively to the abutment, gripping-jaws mounted on said carriage, and means for operating said jaws to stretch the upper.

15. In a machine for stretching uppers, the 85 combination of a reversible support affording an abutment for a last, a reciprocating pin on said support and adapted to engage the last and hold it against the abutment, and means for manipulating said pin.

90 16. In a machine for stretching uppers, the combination of a reversible support affording an abutment for a last, a reciprocating pin on said support and adapted to engage the last and hold it against the abutment, 95 means for moving said pin into engagement with the last, and an automatic lock to hold said pin in such engagement.

In testimony whereof I have signed my name to this specification, in the presence of 100 two subscribing witnesses, this 13th day of January, A. D. 1897.

WILLIAM S. HAMM.
